DESIGN FOR A SHOE

Louis D. Morrell, New York, N. Y., assignor to Bancroft Walker Co., Waltham, Mass., a corporation of Massachusetts

Application October 1, 1935, Serial No. 58,776

Term of patent 3½ years

To all whom it may concern:

Be it known that I, Louis D. Morrell, a citizen of the United States, residing at 230 W. 101 Street, in the city and county of New York and State of New York, have invented a new, original, and ornamental Design for a Shoe, of which the following is a specification, reference being had to the accompanying drawing, forming a part thereof, in which

Fig. 1 is a plan view of a shoe showing my design, and

Fig. 2 is a view of the shoe in side elevation, the heel being shown conventionally in dot and dash lines.

Both sides of the shoe present the same general appearance.

I claim:

The ornamental design for a shoe substantially as shown and described.

In testimony whereof, I have affixed my signature hereto.

LOUIS D. MORRELL.
